UNITED STATES PATENT OFFICE.

MICHAEL B. DYOTT, OF PHILADELPHIA, PENNSYLVANIA.

DESIGN FOR CARBURETERS FOR GAS-BURNERS.

Specification forming part of Design No. **8,018**, dated February 9, 1875; application filed December 16, 1874.
[Term of Patent 7 years.]

To all whom it may concern:

Be it known that I, MICHAEL B. DYOTT, of Philadelphia, Pennsylvania, have invented a Design for Carbureters for Gas-Burners, of which the following is a specification:

The nature of my design is fully illustrated in the accompanying drawing.

The carbureter is to be attached to a gas-burner, the base A fitting over the ordinary gas-tip, and an additional burner being fitted to the top a. The carbureter is made round throughout, and the lower portion, or base A, is separated from the upper portion by a bead, d. The base is rounded at x, and the upper portion is rounded, at y, on a curve which

merges into the inclined or slightly-curved side u, the latter merging, with a curve, t, into the bead d.

I claim—

The design for a carbureter, substantially as herein described, and as illustrated in and by the accompanying drawing.

In testimony whereof I have signed my name to this specification in the presence of two subscribing witnesses.

M. B. DYOTT.
